UNITED STATES PATENT OFFICE

2,465,187

CHILD'S SLIDE

Robert S. Barrabee, Elberon, N. J.

Application April 4, 1947, Serial No. 739,404

6 Claims. (Cl. 272—56.5)

1

This invention relates to improvements in amusement devices for children of that type known in the art as slides, and comprehends a structure capable of an arrangement of parts whereby the structure may be utilized as a duplex slide or as a single slide in tunnel form.

One of the objects of the present invention is to construct a device of knock-down form to permit storage and convenient shipment and which can be quickly assembled or disassembled.

Another object of this invention is to provide a slide of tubular form divided into a pair of hinged symmetrical parts formed by longitudinal division of the cylinder whereby when in opened position these parts may be supported to provide adjacent duplex slide members.

Another object of this invention is to provide supporting means for the slide both in open and closed position and also the provision of steps to facilitate the use of the device, the steps including structure for detachably supporting the elevated ends of the slide.

Other features of the invention will more clearly hereinafter appear by reference to the accompanying drawings forming a part of the specification and wherein like characters of reference designate corresponding parts throughout the several views, in which—

Figure 1 is a side elevation of the assembly.

Figure 2 is an end view showing the steps and supporting structure.

Figure 3 is a section on line 3—3 of Figure 1.

Figure 4 is a section on line 4—4 of Figure 1, including a disclosure in dotted line illustrating the position of the upper slide section when in open position.

Figure 5 is a transverse section showing the hinge support for the upper end of the slide, and

Figure 6 is a view partly in section showing a supporting structure for the lower end of the slide.

Figure 7 is an end view of a modification.

The supporting structure for the amusement device includes a platform 1 having spaced front legs 2 and rear legs 3, these legs terminating at their lower ends in relatively flat enlarged foot portions 4. The front legs 2 support steps 5 which may be suitably spaced and may be of any form, either flat as illustrated or round if the latter structure is preferable. Hand rails 6 are arranged at each side of the steps and extend from adjacent the base of the front legs 2 outwardly and upwardly so that the major portion of each hand rail is substantially parallel to its adjacent legs 2. The upper ends of each hand rail extend above

2

the platform and rearwardly and downwardly to the supporting blocks 7 arranged on top of the platform 1. The blocks 7 are bolted by means of bolts 10 to the platform and are arranged at each side of the slide structure to permit a person using the slide to retain hold of the same while assuming position on the slide structure either in tunnel or open duplex form. At the rear of the platform 1 and connecting the upper ends of the rear legs 3 and the platform 1 is the elongated channel structure 8, which extends along the rear marginal edge of the platform 1 and is secured thereto by any suitable means which will permit it to be detachable from the platform 1. A pair of spaced openings 9 for bolts 10 are provided for detachably securing the slide structure to the channel 8. If desired this channel 8 may be permanently attached to the platform 1.

The slide is in the form of an elongated tubular body bisected horizontally and longitudinally to perform the symmetrical lower and upper parts 11 and 12, respectively. The two sections of the cylindrical slide are hinged together at 14, and for purposes of illustration the hinge barrel is formed by curling adjacent longitudinal marginal edges of the slide sections 11 and 12 in opposite directions at spaced intervals to provide for the reception of the pintle 16. The pintle 16 and hinge barrel 14 may extend the full length of the slide or several spaced hinged portions may be provided for several pintles. In either instance the pintles should be readily removable to permit separation of the sections and nesting of these parts for storage or shipment.

On the upper end of each tunnel section and medially of the end margin are hinged plates 17 and 17' shown in detail in Figures 4 and 5. These plates 17 are constructed and arranged to seat in the slot of the channel 8 and are provided with spaced openings through which the bolts 10 may extend when passing through the opening 9 of the channel. By this arrangement when the slide is in tubular or tunnel form only plate 17 is utilized in supporting the upper end of the structure; however, when the slide structure is opened to provide a duplex slide then the upper plate 17' will be received in the channel and can be locked by the use of bolts extending through the openings 9.

The lower end of each section of the slide is provided with leg members 19 each being formed with sockets 20, as shown in Figure 6, for receiving the upper end of the removably adjustable leg section 21, the latter having the enlarged foot 22 and being locked in adjusted posi-

tion by a hand screw or its equivalent 23. When the structure is in tunnel form, i. e., when the upper slide section overlies the lower slide section, the parts may be retained in place by pins or other forms of fastening 24, such elements 24 preventing lateral displacement of the edges of the slide and preventing the hinged parts from clattering during use.

While the present embodiment illustrates one form of the invention it will be obvious to one skilled in the art that certain details of construction may be modified without departing from the spirit of the invention.

What I claim as new and useful and desire to secure by Letters Patent is:

1. In an amusement slide, said slide comprising a tubular body longitudinally bisected to form sections and hinged means for the sections to permit movement of the upper section to a position to form a second slide member.

2. In an amusement device, a tubular body formed of a pair of symmetrical longitudinal sections, said sections being hinged along one of their adjacent marginal edges to permit opening of the tubular body to provide connected channel slideways, means for supporting the upper end of said sections in both open and closed position, and means for supporting the lower end of said sections.

3. In an amusement device, a tubular body formed of a pair of longitudinal sections, said sections being hinged along one of their adjacent marginal edges to permit opening of the tubular body to form connected upwardly faced channels, a supporting stand for one end of said device, 35

and fastening means for connecting each section of said slide to said supporting stand.

4. In an amusement slide comprising a tubular body formed of a pair of longitudinal sections, 5 said sections being hinged together along one edge to permit opening of the tubular structure to provide a pair of spaced connected upwardly facing channel shaped slideways, means for supporting the upper end of said sections in both open and closed position, and means for securing said sections against lateral displacement when assembled in tubular form.

5. In an amusement slide, a tubular body formed of a pair of longitudinal sections, 15 said sections being hinged together along one edge to permit the parts to be swung to open position to form connected open channel slides, a support for the upper end of said device, said support including a channel, and means fixed to the 20 upper end of each section of said slide for engaging in said channel.

6. The substance of claim 5 characterized in that fastening means are provided for detachably securing the slide sections in said channel.

ROBERT S. BARRABEE.
